MIXING APPARATUS

John D. Allen, Belding, Mich., assignor to Process Equipment Engineers, Inc., Belding, Mich., a corporation of Michigan

Application April 27, 1946, Serial No. 665,499

6 Claims. (Cl. 259—97)

1

This invention relates to mixing apparatus for fluids, and more particularly to agitators for mixing fluids.

The principal object of the present invention is to provide an agitator for fluids in which the rate of agitation can be closely regulated from no agitation to the maximum agitation determined by the power of the driving means for the agitator.

Another object of the invention is to provide an agitator in which the rate of agitation is controlled by valving the fluid rather than by regulating the speed of the agitator prime mover.

Another object is to provide a novel agitator which will provide rapid circulation of the fluid without splashing or foaming.

These objects, and others ancillary thereto, will more fully appear in the following specification when read in connection with the accompanying drawings, wherein:

Figure 1 is a plan view of a fluid mixing apparatus embodying the invention;

Figure 2 is a side elevational view of the apparatus, approximately half of the tank wall being broken away to show the interior thereof; and

Figure 3 is a cross-sectional view taken through the axis of the agitator.

The mixer shown in the drawings constitutes a preferred embodiment of the invention, but it will be understood, as the description proceeds, that the invention is susceptible of a wide variation in the forms which it may take.

The invention is shown as applied to a fluid container in the form of a tank 10 supported on suitable legs 11. The tank is provided with a conduit 12 by which the contents of the tank may be drawn off.

Within the tank and near the bottom thereof, is an agitating mechanism. In general the agitating mechanism comprises an impeller 13, and a housing consisting of upper and lower relatively movable parts 14 and 15. The impeller is driven by a motor 16 located exteriorly of the tank, as will more fully appear presently.

The impeller is a flat plate 17 of circular form on one side of which are mounted a plurality of upstanding angularly spaced vanes or blades 18. In the present instance the vanes are of angular cross-section but it is obvious that they may take other forms. The plate 17 is centrally apertured to receive a hub 19 which is fixedly attached to the plate. The hub 19 rotates within a sleeve 20 which in turn is rotatably mounted in a bearing 21 fixedly secured in an opening in the bottom of the tank 10.

A drive shaft 22 is keyed or otherwise secured to the hub 19 in driving engagement therewith.

2

The lower end of the shaft 22 rotates in a bearing in a bracket 23 mounted beneath the tank. A pulley 24 is secured to the lower end of the shaft 22, and the pulley is driven from the motor 16 by a belt 25. By suitably mounting the motor, the drive therefrom may be direct, rather than by means of a belt.

As above mentioned, the housing for the impeller comprises generally an upper part 14 and a lower part 15. The upper part 14 consists of an intake end wall 26 of slightly greater diameter than the impeller 13, and a peripheral flange 27 of somewhat greater axial extent than that of the impeller. A relatively large central opening 28 is cut in the intake end wall 26.

A circular baffle plate 29 is mounted over the opening 28 in spaced relation to wall 26, by means of brackets 30.

On two opposite sides of the upper part 14 of the housing are guide brackets 31. The guide brackets have openings 32 therein which receive a pair of guide posts 33. The latter are secured to the bottom of the tank in any suitable manner. The guide brackets 31 and guide posts 33 prevent rotation of the upper part of the housing, while permitting movement thereof axially of the impeller 13.

The lower part 15 of the housing consists of a flat plate apertured at its center to receive the sleeve 20, heretofore mentioned. The part 15 is fixedly secured to the sleeve and rotates therewith, as will appear presently. The diameter of the lower part 15 is somewhat greater than that of the upper part 14.

Two slotted cam members 34 and 34a are fixedly secured to the part 15 of the housing at radially opposite edges thereof. Cam member 34a has a single inclined slot 35a, while cam member 34 is formed to provide two inclined, parallel slots 35 which extend from points adjacent the part 15 upwardly a substantial distance. Cam followers 36 and 36a in the form of cylindrical pins are secured to the flange 27 of the upper part of the housing and are received in the slots 35 and 35a.

A handle 37 for rotating the part 15 of the housing is mounted beneath the tank. The handle 37 is provided at one end with an opening which receives the lower end of the sleeve 20, as shown in Figure 3. The edge of the opening is provided with notches 38 (Figure 1), which receive depending lugs 39 (Figures 2 and 3) so that angular movement of the handle 37 will produce rotation of the sleeve.

The handle 37 is supported by suitable brackets 40 and 41. The latter is provided with a series of openings 42 which cooperate with a pin 43 by

means of which the handle may be fastened in any predetermined position.

When the tank 10 is filled with liquid to a level above the top of the upper part 14 of the housing of the impeller, and the motor is started, the impeller will drive the liquid that fills the space between the vanes 18 radially outwardly toward the sides of the tank where it will be deflected upwardly (for the most part) and downwardly. Liquid will be drawn from the upper part of the tank, through the intake opening 28 in the housing, into the impeller to replace that discharged by the impeller. Thus, a continual circulation of fluid throughout the tank will be achieved.

When the parts of the agitator are in the positions shown in Figures 2 and 3 the rate of agitation will be at its maximum, and will be limited only by the power of the motor 16 and by the volume of liquid which can escape between parts 14 and 15 of the housing. The rate of agitation may be reduced, however, by moving the handle 37 from its full line position in Figure 1 toward its dotted line position. Rotation of handle 37 in that manner imparts a corresponding rotation of lower part 15 of the housing and cams 34, which pulls the cam followers 36 and 36a and the upper part 14 of the housing downward toward the lower part. The part 14 cannot rotate because such movement is prevented by guide brackets 31 and guide posts 33. Thus, when the part 14 is forced downward, the space between part 15 and the flange 27 is reduced, thereby reducing the volume of fluid which escapes from the impeller. If the part 14 is moved downward into contact with part 15, agitation of fluid is completely stopped, except for that very small quantity of fluid trapped within the housing.

Thus it will be seen that the present invention furnishes an agitator in which the rate of agitation of the fluid in the tank can be easily regulated. The motor can, of course, be of the relatively inexpensive constant speed type. The manner in which the fluid circulates eliminates splashing and foaming of the fluids in the tank. The invention can be employed with any shape of tank.

The scope of the invention is indicated in the appended claims.

I claim:

1. A mixer for fluids comprising a fluid container, said container having an opening in a wall thereof, an agitator in said container, said agitator comprising a rotary impeller affixed to a shaft extending through said opening, a housing for said agitator, said housing including a first wall comprising a centrally apertured radial plate positioned adjacent the intake side of said impeller and an annular flange surrounding the periphery of said impeller, a second wall comprising a radial plate positioned on the side of said impeller opposite said first wall and having a portion surrounding said shaft and projecting through the opening in the container, said second wall being rotatable and axially movable relative to said first wall, means connecting said walls whereby relative rotation thereof causes relative axial movement thereof, and means outside of said container connected to said portion of said second wall for rotating the latter.

2. A mixer as defined in claim 1 wherein the means for causing relative movement of said walls comprises a slotted cam on one wall and a cam follower on the other wall positioned in said slot.

3. A fluid agitator comprising a rotary impeller and a housing therefor, said housing comprising an intake end wall and a discharge end wall extending radially of said impeller at axially opposite ends thereof, said intake wall having an axial opening therein, a continuous circumferential wall surrounding the periphery of said impeller and secured to said intake wall, said circumferential wall normally being spaced from said discharge end wall and movable axially relative thereto, and means for moving said last named two walls to close and open the space therebetween, said means comprising rotary cam means on said circumferential and discharge end walls.

15 4. A fluid agitator comprising a rotary impeller and a housing therefor, said housing comprising an intake end wall and a discharge end wall extending radially of said impeller at axially opposite ends thereof, said intake wall having an axial opening therein, a continuous circumferential wall surrounding the periphery of said impeller and secured to said intake wall, said circumferential wall normally being spaced from said discharge end wall and movable axially relative thereto, and means for moving said last named two walls to close and open the space therebetween, said means comprising rotatable slotted cams on one of said last named two walls and cam followers on the other of said last named two walls located in said slots, one of said walls being movable angularly relative to the other wall.

25 5. A mixer for fluids comprising a fluid container, an agitator therein, said agitator comprising a rotary impeller and a housing therefor, said housing comprising a first wall including a radial centrally apertured plate positioned adjacent the intake side of the impeller and an annular flange surrounding the periphery of said impeller, a second wall paralleling said plate and arranged on the axially opposite side of the impeller, means connecting said walls together for movement relative to each other in a direction axially of each other, and means comprising cam members connected to said walls for imparting 45 such axial movement to said walls.

6. A mixer for fluids comprising a fluid container, an agitator therein, said agitator comprising a rotary impeller and a housing therefor, said housing comprising a first wall including a radial centrally apertured plate positioned adjacent the intake side of the impeller and an annular flange surrounding the periphery of said impeller, a second wall paralleling said plate and arranged on the axially opposite side of the impeller, means connecting said walls together for movement relative to each other in a direction axially of each other, and means for imparting such relative axial movement to said walls, said last named means comprising a slotted cam member attached to one wall and a cam follower on the other wall received in said slot, one of said walls being rotatable and axially movable relative to the other wall.

JOHN D. ALLEN.
